(57) **CLAIM**

The ornamental design for a misting device, as shown and described.

DESCRIPTION

FIG. 1 is a perspective view of a misting device showing our new design;

FIG. 2 is a front elevation view thereof;

FIG. 3 is a rear elevation view thereof;

FIG. 4 is a first side elevation view thereof;

FIG. 5 is a second side elevation view thereof;

FIG. 6 is a top plan elevation view thereof; and,

FIG. 7 is a bottom plan view thereof.

The dashed broken lines depict portions of the misting device that form no part of the claim.
